UNITED STATES PATENT OFFICE.

CHARLES H. ROBINSON, OF ST. PAUL, MINNESOTA.

FEED-WATER HEATER.

SPECIFICATION forming part of Letters Patent No. 329,438, dated November 3, 1885.

Application filed January 31, 1885. Serial No. 154,573. (No model.)

To all whom it may concern:

Be it known that I, CHARLES HENRY ROBINSON, a citizen of the United States, and a resident of St. Paul, in the county of Ramsey 5 and State of Minnesota, have invented certain new and useful Improvements in Feed-Water Heaters, of which the following is a specification.

In the drawings, Figure 1 is a sectional elevation on the line $x-x$ of Fig. 2. Fig. 2 is a cross sectional view on the line $y-y$ of Fig. 1.

This invention relates to apparatus used to heat and purify the feed-water of steam-boilers, and particularly to that class of such devices known as "closed" or "pressure" heaters; and it consists in the construction and arrangement of parts substantially as hereinabove shown and described.

To illustrate my invention, I have shown in 20 the drawings a wrought-iron or steel outer shell or jacket, A' , having a wrought-iron or steel top, A^2 , and a cast-iron bottom, A^3 . If preferred, the top and bottom A^2 A^3 may both be made of steel or wrought-iron or both of 25 cast-iron. The base A^3 will be provided at its center with an opening, into which the exhaust-pipe B' from the engine is secured by a packed coupling, a' .

B' is another pipe, connected into the opening in the base A^3 , and running upward therefrom, and forming a continuation of the exhaust-pipe B' . The base A^3 also has a discharge-opening or nozzle, C , to which the discharge-pipe will be attached for conveying 35 the steam away from the jacket after it has performed its work. Inside the jacket A' is a heater-shell, D' , supported by legs b' , the shell being less in length and diameter than the jacket, so that an annular space is left 40 between the jacket and the sides of the shell, and a chamber, d' , between the top A^2 and the top of the shell, and a similar chamber, d^2 , between the bottom A^3 and the bottom of the shell. Thus a steam space is left between the 45 jacket and shell on all sides. Legs or supports b^2 will be attached to the top of the shell D' and projected upward and outward in contact with the inside of the jacket A' to support the shell D' in the jacket and assist to 50 keep it in its proper place, and in connection

with the legs b' hold the shell fixed in its proper place in the jacket, especially during transportation, when the heater is liable to be placed horizontally or in a reversed upright position.

55
 E' is a large internal flue connecting the ends of the shell D' and forming a large opening through it, and up through which the pipe B^2 leads, as shown. The flue E' is larger than the pipe B^2 , so that an annular space is left 60 between them. The pipe B^2 is shown ending a short distance below the upper end of the shell D' and flue E' ; but its length may be varied to suit circumstances.

E^2 E^3 are a series of smaller tubes or flues 65 connecting the heads of the shell D' and forming communications through them for the steam between the chambers d' and d^2 . These flues E^2 are arranged only on three sides of the large flue E' , leaving an open space, g , on 70 one side unoccupied by flues.

F' is the feed-pipe through which the water is fed to the shell D' , and F^2 is the delivery-pipe through which the water is forced into the boiler. The delivery-pipe F^2 is suitably 75 packed where it passes down through the head A^2 and the top of the shell D' , while the feed-pipe F' is arranged to pass down through a large tube or pipe, G , the latter in turn passing down through the head A^2 and the 80 top of the shell D' . The tube G is larger than the pipe F' , so that an annular space is left between them, as shown. The tube G is suitably packed where it passes through the head A^2 , and secured into the top of the shell D' 85 and made steam-tight in the ordinary manner, and the pipe F' is suitably packed where it passes through the head of the tube G . By this arrangement of the tubes F' and G only one opening is required through the head A^2 90 and the top of the shell D' to accommodate both, and also permits the feed-water to be supplied to the shell and the surface "blow-off" to be taken out through the same space, as hereinafter shown.

95
 m is a small pipe leading from the upper end of the tube G , through which any scum or animal or vegetable matter rising to the top of the heater may be discharged. The delivery-pipe F^2 projects down into the shell 100

for a short distance, so as to take the water from the shell some distance below the top, as it is more nearly free from impurities at this point, as hereinafter shown. The feed-pipe F' is also arranged to project down into the water some distance, so as to deliver the water to the shell below the surface, and prevents the disturbance of the water in the upper part of the shell.

H is a large tube, open at the top and closed at the bottom, and supported in the open space g in the shell D' by legs or supports n , the latter spreading outward and resting against the shell D' and tubes E' and E^2 in such a manner as to support the tube in the shell and hold it in its proper place in whatever position the heater may be placed. The lower end of the feed pipe F' projects down into this tube H , and the lower end of the latter is perforated, as shown at t , to permit the water to freely circulate through it and also to permit the water to be drawn therefrom when the heater is to be emptied. The base A^3 , it will be observed, is provided with a leg, A^4 , cast in one piece therewith, by which the heater is supported on one side, the remaining sides being supported by legs A^5 , bolted to the base. The shell D' may be easily removed from the jacket A' by removing the bottom A^3 , and the tube G and pipes F' and F^2 .

I obtain many important advantages by this manner of constructing a heater, among others, the following: By this arrangement all parts of the shell D' is heating-surface, as it is entirely surrounded by the steam; hence there is no loss by radiation. By carrying the tube B^2 upward through the shell D' , I save and impart to the tube E' , and through it to the water in the shell D' , all the heat radiated from the tube B^2 . By discharging the steam upward into the chamber d' it spreads outward and completely fills the chamber, and passes down the flues E^2 and between the flue E' and pipe B^2 , and also between the jacket A' and shell D' equally, thus heating all parts of the shell D' and its flues uniformly and to an even temperature, thereby preventing unequal expansion and contraction. This is a very important feature of my invention, as any unequal expansion and contraction of the tubes and shell would result in the loosening of the joints and the ultimate destruction of the heater. By carrying the steam downward through the flues E' and E^2 and around the shell D' all the water of condensation is carried down with it and not permitted to accumulate upon or remain in contact with the flues or shell. On the contrary, where the flow of steam currents is upward, the water of condensation runs downward against the steam-currents, and is retarded thereby and held in contact with the flues and shell for a greater length of time, thus cooling them and causing unequal contraction, which frequently results in opening the joints and causing a disagreeable cracking or pounding noise. The

steam by being first discharged upon top of the shell D' heats the water in the upper part to a slightly higher degree of temperature than that in the lower part, thereby causing the water to constantly circulate in the shell and renders its absorption of heat more rapid.

Another important element in the production of the circulation of the water in the shell is the absence of the flues E^2 in the space g , as the water in this space remains comparatively undisturbed, while the water surrounding the tubes E^2 is kept in a constant commotion by the radiation of the heat therefrom. This action causes the water surrounding the tubes E^2 to be arranged into upward currents, which flow over and down into the undisturbed space g , and of course cause the water from this space to flow downward and over and upward among the tubes E^2 , thus causing a complete circulation. While passing down through the space g , the water being in less rapid commotion and moving more slowly than when passing upward on the other side, the foreign matter contained in it has an opportunity to become separated therefrom, the heavier mineral and similar substances falling to the bottom of the space g will be drawn off at suitable intervals by a pipe, K , while the lighter vegetable and animal matter rising to the top will be drawn off through the tubes G and m . The shell D' will be large enough to supply the boiler with which it is connected long enough to permit the water to be held in the shell until it is heated to as high a degree as it is possible for exhaust-steam to heat it. Usually exhaust-steam is capable of imparting to the water in the shell a temperature of from 208° to 216° Fahrenheit, and the water in the shell D' can be raised to this degree in about twenty minutes; hence the shell D' should be large enough to hold a sufficient quantity of water to supply the boiler for about twenty minutes, and also hold the water in the heater long enough to be purified. The impurities ordinarily found in the water-supply of boilers separate therefrom at about the boiling-point, or at a temperature of 212° Fahrenheit; hence by heating the feed-water to that degree the impurities will usually be separated therefrom, the heavier particles falling to the bottom and the lighter substances rising to the surface. Thus the water a short distance down from the top is more nearly free from impurities than the remainder, which is the reason why the delivery-pipe F^2 is arranged to take the water for the boiler from this point, thus feeding purified water only to the boiler, and preventing the accumulation of scale therein.

Another advantage gained by taking the water from near the top of the shell D' is that the boiler is thereby fed with the hottest water in the shell, and any loss which would result from the necessity of reheating in the boiler is saved.

Another important feature of this invention is the presence of the tube H with the feed-

pipe F' leading down into it, as the cold water is thus kept separated from the mass of the water until it is heated to a temperature nearly as great as the remainder of the water before it mingles with it. Thus none of the cold water comes in contact with the flues. After being thus heated the water flows outward from the tube H and mingles with the downward currents in the space g, and does not create a disturbance therein. The water is confined in the tube H until nearly all the agitation caused by the inflowing water has ceased and the water formed into downward currents, which mingle with the downward currents in the space g and prevent any commotion or interference with the natural course of the water, as before described. Thus the impulse of the feed-water is downward and runs into a downward current, which is a very desirable reslt.

I claim as my invention—

1. A heater-shell provided with flues open at both ends and extending therethrough from end to end, and water feed and discharge pipes communicating with said shell, in combination with a casing or jacket inclosing said shell, and of a greater length than said shell, whereby chambers are formed above and below said shell, a steam-inlet pipe which enters the bottom of said jacket, a flue or flues within the jacket which convey the steam from said inlet-pipe to the chamber above the heater-shell, and a steam-exhaust port leading from the chamber below the heater-shell, substantially as set forth.

2. A heater-shell, and a steam jacket or casing inclosing the same, in combination with steam inlet and discharge pipes which communicate with the interior of the casing or jacket through the bottom thereof, and water feed and discharge pipes which pass through the top of the casing or jacket and communicate with the heater-shell through the top thereof, substantially as set forth.

3. A heater-shell provided with flues open at both ends, and extending therethrough from end to end, and a casing or jacket inclosing said shell, of a length greater than said shell, whereby chambers are formed above and below said shell, in combination with water feed and discharge pipes which pass through the top of the casing and communicate with the heater-shell through the top thereof, a steam-inlet pipe which enters the bottom of said jacket, a flue or flues within the jacket which convey the steam from the inlet-pipe to the chamber above the heater-shell, and a steam-exhaust port leading from the chamber below the heater-shell, substantially as set forth.

4. In a feed-water heater, a heater-shell formed with a large central flue, and with smaller side flues between said central flue and the periphery of the shell, said flues being open at both ends and extending through said shell from end to end, and feed and discharge water-

pipes communicating with said shell, in combination with a casing or jacket inclosing said shell, of a length greater than said shell, whereby chambers are formed above and below said shell, a steam-admitting pipe which enters the bottom of said casing and conveys the steam to said central flue, and a steam-discharge pipe at the bottom of said casing, whereby the current of steam is upward through said central flue and downward through said side flues, substantially as set forth.

5. In a feed-water heater, a heater-shell formed with a large central flue, and with smaller side flues between said central flue and the periphery of the shell, said flues being open at both ends and extending through said shell from end to end, and feed and discharge water pipes communicating with said shell, in combination with a casing or jacket inclosing said shell, of a length greater than said shell, whereby chambers are formed above and below said shell, and of a greater diameter than said shell, whereby an open space is left between the sides of said shell and casing, a steam-admitting pipe which enters the bottom of said casing and conveys the steam to said central flue, and a steam-discharge pipe at the bottom of said casing, whereby the current of steam is upward through said central flue and downward through said side flues and the space between the sides of the casing and shell, substantially as set forth.

6. In a feed-water heater, a heater-shell, in combination with a water-discharge pipe which passes through the upper end or head of said shell, and which extends into said shell, and has its opening at a point below the surface of the water in the shell and away from the sides of the shell, substantially as set forth.

7. In a feed-water heater, a heater-shell, in combination with water feed and discharge pipes which pass through the upper end or head of said shell, and which extend into said shell, and have their openings at points below the surface of the water in the shell and away from the sides thereof, substantially as set forth.

8. In a feed-water heater, a heater-shell, in combination with a large tube suspended therein, and a feed-water pipe which enters said heater-shell and extends into said tube, whereby the cold water is admitted into said tube, substantially as set forth.

9. In a feed-water heater, a heater-shell, D', having flues through a portion only of its interior, whereby an open space, g, is left therein, water-feed pipe F', tube H, and discharge-pipe F', substantially as set forth.

10. In a feed-water heater, the combination of jacket A', head A', shell D', having flues E' E'', tube G, connecting said jacket with the outer air, and feed-water pipe F', passing down through said tube G into said shell, substantially as set forth.

11. In a feed-water heater, a base having one of the legs cast in a single piece therewith, and with a passage extending from the upper surface of said base outward through said 5 leg, which passage constitutes the steam-discharge passage, substantially as set forth.

12. The combination of a jacket, A', head A², heater D', having flues E' E², base A³, having leg A⁴, and discharge opening C, cast

in one piece therewith, pipes B' B², packing 10 a', and legs A⁵, substantially as set forth.

In testimony whereof I have hereunto set my hand in the presence of two subscribing witnesses.
